Primary Examiner — Raphael Barkai

(74) Attorney, Agent, or Firm — Nixon & Vanderhye, P.C.

(57) **CLAIM**

The ornamental design for a television set, as shown and described.

DESCRIPTION

FIG. 1 is a front, left perspective view of a television set in accordance with our new design;

FIG. 2 is a front elevation view thereof;

FIG. 3 is a back elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a sectioned right side view taken along line **8-8** of FIG. 2;FIG. 9 is a sectioned right side view taken along line **9-9** of FIG. 3; and,FIG. 10 is a sectioned bottom view taken along line **10-10** of FIG. 3.**1 Claim, 8 Drawing Sheets**| (56)	References Cited
